SEED POTATO CUTTER

Edward Martin, Oconomowoc, Wis.

Application October 10, 1940, Serial No. 360,651

1 Claim. (Cl. 146—169)

This invention relates to a cutter primarily for seed potatoes and it aims to provide a novel construction which will permit the cutting of small potatoes or large sized Idaho type potatoes, a construction which is simple and relatively inexpensive, one which is foldable so as to occupy minimum space when not in use, one which is effectively braced and stable at opposite ends of the cutting means, and a construction which is generally improved as will more specifically appear hereinafter.

One operative embodiment is illustrated in accompanying drawing, wherein:

Figure 1 is a perspective view of the device;

Figure 2 is a substantially central longitudinal vertical sectional view;

Figure 3 is a cross section taken on the plane of line 3—3 of Figure 2;

Figure 4 is a fragmentary plan particularly looking upon the cutting means, and

Figure 5 is an inverted plan view particularly showing the press block.

Referring specifically to the drawing, wherein like reference characters designate like or similar parts, the device is generally made in the form of a stand having a top or table as at 10 of any suitable size and shape. Said table is supported by leg structures 11, adjacent opposite ends, such structures having cross battens 12 to which and the top 10, hinges 13 are connected. These structures 11 also have cross battens at 14 to which inclined braces 15 are bolted as at 16 and which braces are also bolted as at 17 to the top 10. It will be realized that the braces 15 may be removed or detached at one end, to enable the leg structures 11 to be folded relatively flat against the top 10 in order that the structure will occupy minimum space when shipped or stored, especially between planting seasons.

Said top 11 has an opening 18 therethrough and also has kerfs 19 extending downwardly from the top on opposite sides of the opening 18 and another kerf at 20 extending longitudinally of the top from one end of said opening 18. Secured friction tight or in any suitable manner in the kerfs 19, are transverse cutter blades 21, three of which are joined by a longitudinal cutter blade 22, having an end anchored friction tight or otherwise in the kerf 20. The cutter blades 21 and 22 are preferably made of stainless steel. The potato to be cut is adapted to be disposed over the blades 21 in the most advantageous po-

sition according to the number and size of the pieces into which it is to be cut.

A lever 23 is pivoted at 24 to a U-shaped mounting 25 fastened as at 26 to the top 10. Such lever is urged upwardly at its rear end by means of an expansive coil spring 27 bearing against the under surface thereof and anchored in a recess 28 in the top 10. At the rear end, lever 23 carries a press block 29 and the lower surface thereof is provided with grooves at 30 and 31, to match the blades 21 and 22, respectively, although being relatively wide with respect to such blades.

An operating handle is provided at 32, and said operating handle 32, lever 23 and block 29 are secured together by common screws or other fastenings as at 33.

In the operation of the machine, potatoes with one hand are advantageously positioned over the blades 21 and 22 while the other hand depresses the lever 23 and causes block 29 to engage the potatoes and press them against the blades 21 and 22 and through the spaces therebetween and space 18, falling into a suitable receptacle disposed beneath the opening 18. Following such operation, the spring 27 will restore the lever 23, block 29 and handle 32 to raised position preparatory to cutting the succeeding seed potato. It will be particularly noted that the upper ends of the braces 15 are relatively close to the opening 18 and hence the structure is effectively braced and rendered relatively rigid, at opposite ends of the zone of cutting.

Various changes may be resorted to provided they fall within the spirit and scope of the invention.

I claim as my invention:

A cutter of the class described having a table provided with an opening, kerfs adjacent the opening, cutter blades secured in the kerfs and crossing the opening, a U-shaped bracket rising from the table, a lever extending into and pivoted to the bracket, a block carried by the lever to press potatoes against the blades, a handle, fastenings common to the block, lever and handle, spring means between the table and lever urging the latter and block away from the blades, foldable leg means pivoted to the underside of the table, and displaceable brace means for the leg means secured to the table in downwardly diverging relation adjacent opposite ends of the opening, to reinforce the table at the zone of cutting.

EDWARD MARTIN.
